UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

COMPRESSION RELIEF VALVE.

Application filed September 16, 1925. Serial No. 56,656.

This invention relates to rock drills, but more particularly to motive fluid distributing valves and compression relief valves for fluid actuated rock drills of the hammer type.

5 The objects of the invention are to produce a compression relief valve of the rocking type which may be actuated by the direct application of live pressure fluid from the supply against the pressure surface formed by one side or the other of the said valves in order to throw the valves quickly and with certainty and precision. Other objects of the invention are to produce a light quick operating valve which is cheap 10 to manufacture and yet is strong and durable.

The invention is illustrated in one of its preferred forms in the accompanying drawings in which

20 Figure 1 is a longitudinal sectional side elevation partly broken away of so much of a rock drill as will serve to illustrate the invention, taken on the line 1—1 of Figure 2 looking in the direction of the arrows,

25 Figure 2 is a transverse sectional plan view of Figure 1 on the line 2—2 looking in the direction of the arrows,

30 Figure 3 is a view similar to Figure 1 with the piston and ring valve in different positions, and

Figure 4 is a view similar to Figure 2 with the valves in different positions.

Referring to the drawings, the cylinder A is provided with a piston B preferably of the 35 hammer type having the forward extension or shank C extending through the front cylinder washer D to impart blows of impact to the usual drill steel. In this instance, rifle bar rotation is shown including the rifle 40 bar E and the rotation ratchet F and rotation head G, which two latter parts are located within the back head H. A back head plate J covers the rotation mechanism and in this instance the valve mechanism is shown with- 45 in the head block K which holds the water tube L and also contains the throttle valve O. A sleeve P is preferably placed around the water tube and is seated in the plate J and head block K to seal the interior of the 50 ring valve Q from the remaining parts of the drill, since the ring valve in this instance is shown surrounding the water tube. A shallow flat valve cage R as shown is located within the shallow valve chest portion

of the head block K and this valve cage contains a cavity S which is generally circular in form, but is preferably not a true circle. This cavity forms the valve chamber for the valve Q which valve is preferably of annular shape and forms a true circle.

55 The cavity or main central bore S of the valve cage is preferably formed by the intersection of two circles of the same diameter so that the opposed portions T and U of the cavity S are semi-circles joined at the points V and W by flat portions, although these flat portions cannot be clearly indicated in the drawings owing to the scale to which the drawings are made. The two halves T and U of the boundary walls of the cavity S 60 need not necessarily be semi-circular but for the best results, the radius of curvature of each approximate half T and U should substantially be the same.

65 The valve cage R is of shallow depth since the valve is intended to be light, thin and flat and is preferably truly circular having the same radius of curvature as that of the opposed end portions T and U of the valve chamber so that the valve may reciprocate 70 transversely in said chamber and will fit snugly in each semi-circular portion of the chamber. The valve as shown reciprocates transversely to the longitudinal axis of the bore of the valve cage, which axis as indicated in Figures 2 and 4 does not exactly coincide with the longitudinal axis of the 75 drill cylinder owing to the fact that a compression relief valve X is also located within the head block K at one side of the ring 80 valve Q.

85 Ports Y and Z in the valve cage are open through the semi-circular walls of the valve chamber and are controlled by the faces of the reciprocating ring valve. The ring 90 valve is comparatively flat and of substantially greater diameter than width, in this instance, the width of the valve being taken as the height of the valve. The thickness 95 of the valve is understood to be the thickness of the walls of the valve and in this instance the valve is shown of exaggerated thickness and substantially rigid, but, if desired, the walls of the valve may be made so thin that the valve is elastic and may be flexed by the 100 fluid pressure passing through it so that in case there is any slight discrepancy between the curvature of the circular walls of

- the valve cage and the curvature of the valve itself, the valve will be slightly distorted by pressure fluid and will be pressed tightly over one or the other of the ports Y or Z .
 5 The valve Q is preferably provided with serrated edges indicated by the slots a with projections between the slots so that pressure fluid entering from the throttle valve O through the admission port b passes into the inside of the valve and through the slots a to the outside of the valve and thence through one or the other of the inlet ports Y or Z , through passages c or d to one end or the other of the cylinder. When one of the 10 passages c or d is an inlet passage, the other forms a compression relief passage.

The compression relief valve X in the form of a rocking valve is contained in the valve chamber e formed in this instance between the valve cage R and the circular wall f of the back head K , which contains the relief ports g and h controlled by said valve. The relief chamber e is alongside of and in the transverse plane of the main central bore S . Ports j and k connect the ports Y and Z with the compression relief valve chamber e and the valve X has an outer convex curved face o of less radius of curvature than that of the inner concave face f of its valve chamber so that as the valve X rocks on its pivot p , the relief ports g and h are controlled by the valve. Pivot p forms a substantial closure or seal dividing the valve chest into two chambers and the valve X is actuated by live pressure fluid acting through the ports j and k directly upon the inner surface of one side or the other of the relief valve. The pressure surfaces of the valve are measured by the distance from the center of the pivot p to the periphery of the valve chest.

In the operation of the device let it be assumed that the piston B is in the position indicated in Figure 1 and is about to start on its forward stroke. The main free exhaust q in the cylinder controlled by the piston is open so that the pressure is reduced to atmosphere at the left hand side of the valve Q as Figure 1 is viewed. Pressure fluid entering the valve through the admission port b will force the valve to the left as indicated in Figures 1 and 2, closing the inlet port Z and opening the inlet port Y . Pressure fluid is thus admitted to the rearward end of the cylinder and the piston is driven forward to the position indicated in Figure 3, having overrun the exhaust port q . Compression in the forward end of the cylinder is relieved through the passage d and thence through the port Z and connecting port k to the relief valve chamber e , and thence to atmosphere through the relief port h , which is open for this purpose because live pressure fluid through the ports 55 Y and j against the opposite wing of the

relief valve has forced the valve to the position indicated in Figure 2 closing the relief port g .

When the piston B overruns the exhaust port q , pressure on the right hand side of the valve Q , as Figure 3 is viewed, is reduced to atmosphere and the valve is thrown by live pressure fluid to the position indicated in Figures 3 and 4 thus admitting live pressure fluid through the passage d 75 to the forward end of the cylinder and at the same time the compression relief valve X is rocked to the position indicated in Figure 4. The piston travels on its rearward stroke and compression in the rearward end of the cylinder is relieved through the compression relief port g after which the cycle is repeated.

I claim:

1. In a fluid actuated rock drill, the combination of a cylinder and reciprocating piston, a main piston controlled exhaust for said cylinder, a distributing valve, and means for relieving compression in the cylinder comprising a valve chest having a curved wall, relief ports in said wall, a rocking compression relief valve pivoted in said chest and having an outer convex valve controlling face of less radius of curvature than the inner concave curved wall of said chest, and means for rocking said valve by pressure fluid.

2. In a fluid actuated rock drill, the combination of a cylinder and reciprocating piston, a main piston controlled exhaust for said cylinder, a distributing valve, and means for relieving compression in the cylinder comprising a valve chest having a curved wall, relief ports in said wall, a rocking compression relief valve pivoted in said chest and having an outer convex valve controlling face of less radius of curvature than the inner concave curved wall of said chest, and means for rocking said valve by the direct pressure of live motive fluid against the inner surface of one side or the other of said valve.

3. In a fluid actuated rock drill, the combination of a cylinder and reciprocating piston, a main piston controlled exhaust for said cylinder, a distributing valve, and means for relieving compression in the cylinder comprising a valve chest having a curved wall, relief ports in said wall, a rocking compression relief valve pivoted in said chest and having an outer convex valve controlling face of less radius of curvature than the inner concave curved wall of said chest, the pivot of said valve forming a seal dividing the valve chest into two chambers, and means for rocking said valve by subjecting the inner surface of one side or the other of the valve to the direct pressure of live motive fluid admitted to one valve chamber 115 while the other is open to exhaust.

4. In a fluid actuated rock drill, the combination of a cylinder and reciprocating piston, a flat valve chest having a bore formed with opposed semi-circular portions, a flat rocking compression relief valve in said separate valve chamber operatively associated with said annular valve, and live pressure fluid ports connecting said valve chest 30 with the ends of said compression relief valve for actuating said valve.
5. In a fluid actuated rock drill, the combination of a cylinder and reciprocating piston, a shallow flat valve chest having a main 35 central bore formed with opposed curved portions, ports in said curved wall portions, an annular valve in the valve chest reciprocating between said curved wall portions and having the same radius of curvature as 40 said wall portions, said valve chest having a separate relief valve chamber located alongside of and in the transverse plane of the main bore, a flat rocking compression relief valve associated with said annular valve, 45 and live pressure fluid ports connecting said valve chest with the ends of said compression relief valve for actuating said valve.
6. In a fluid actuated rock drill, the combination of a cylinder and reciprocating piston, a shallow flat valve chest having a main 35 central bore formed with opposed curved portions, ports in said curved wall portions, an annular valve in the valve chest reciprocating between said curved wall portions and having the same radius of curvature as 40 said wall portions, said valve chest having a separate relief valve chamber located alongside of and in the transverse plane of the main bore, a flat rocking compression relief valve associated with said annular valve, 45 and live pressure fluid ports connecting said valve chest with the ends of said compression relief valve for actuating said valve.

In testimony whereof I have signed this specification:

CHARLES C. HANSEN.
